UNITED STATES PATENT OFFICE.

JOSEPH MALICKI, OF CICERO, ILLINOIS, ASSIGNOR TO TEMPLETON, KENLY & COMPANY, LIMITED, OF CHICAGO, ILLINOIS, A CORPORATION OF ILLINOIS.

JACK.

1,325,951.

Specification of Letters Patent. Patented Dec. 23, 1919.

Application filed May 3, 1918. Serial No. 232,198.

To all whom it may concern:

Be it known that I, JOSEPH MALICKI, a citizen of the United States, residing at Cicero, in the county of Cook and State of Illinois, have invented certain new and useful Improvements in Jacks, of which the following is a specification.

The invention relates to the general art of lifting appliances, and has reference more particularly to that type of lifting appliances commonly known as double-action ratchet-jacks that are used for lifting and lowering heavy loads. The present invention is chiefly concerned with the mechanism that controls the operations and functions of the lifting and lowering and the dogging pawls, and the principal object of the invention is to provide an improved pawl-controlling mechanism that shall render the action of the pawls positive and certain in both the lifting and lowering operations and shall preclude the possibility of simultaneous disengagement of both pawls from the ratchet bar or wheel, such as would cause the jack to lose control of the load being raised or lowered. More specifically, the present invention belongs to that type of jacks wherein the two pawls are connected by a single elastic extensible and contractible link which is provided with a manual control through which the action of said link on the pawls is changed so as to cause them to engage the ratchet-bar or wheel in either a lifting or lowering manner, as desired; and another object of the invention is to provide a novel and improved pawl-controlling link of the character mentioned. Another object of the invention is to provide an improved auxiliary load-engaging appliance designed for removable attachment to and coöperation with the head of the lifting-bar that shall enlarge the field and range of action of the implement and enable it to be readily employed in situations where otherwise its use might be difficult or impossible. With these and other objects in view which will be apparent from the following detailed description my invention consists in the novel structural features, parts and combinations of a jack substantially as hereinafter described, shown as to a practical and preferred embodiment in the accompanying drawings, and defined as to subject-matter and scope in the appended claims.

Referring to the drawings:—

55

Figure 1 is a side elevation, in vertical section through the near side of the casing, of a geared jack embodying my present improvements;

Fig. 2 is a horizontal section on the line 60 2—2 of Fig. 1;

Fig. 3 is a detail side elevation of the pawl-controlling link;

Fig. 3^a is a detail cross-section on the line 65 x—y of Fig. 3;

Fig. 4 is a sectional detail on the line 65 4—4 of Fig. 1;

Fig. 5 is a detail elevation, broken out between its ends, of the handle lever;

Fig. 6 is a top plan view of the head or 70 cap of the lifting-bar.

Figs. 7 and 8 are detail views of the ratchet-wheel, pawls, and pawl-controlling and actuating devices, showing respectively the relative positions of the parts at the 75 downward and upward limits of the swing of the handle lever when the pawl-control mechanism is set for the lifting operation.

Figs. 9 and 10 are detail views similar to Figs. 7 and 8, showing respectively the relative positions of the parts at the upward and downward limits of the swing of the handle lever when the pawl-control mechanism is set for the lowering operation.

Fig. 11 is a detail side elevation of the 85 dogging pawl.

Referring to the drawings, 10 designates as an entirety the frame or housing of the jack that is formed with a vertical slideway 11 in which the lifting-bar 12 is adapted to 90 reciprocate, and, in its upper portion, with an approximately circular chamber 13 that contains certain of the operating parts. A shaft 14 journaled in the opposite side walls of the chamber 13 carries a pinion 15, preferably formed integral therewith, that meshes with the rack teeth 16 on the forward face of the lifting-bar 12, by means of which the latter is actuated, and said shaft also has rigidly keyed thereon a 100 ratchet wheel 17; this construction substantially following that disclosed in Letters Patent to Templeton, No. 1,143,558, dated June 15th, 1915.

Fitted in the opposed openings 18 in the 105 side walls of chamber 13 are hardened steel bearings 19 locked against turning by keys 20, and in said bearings are journaled the

trunnions 21 of a socket-piece 22 that receives the removable handle lever 23; this construction being substantially like that shown in my former Patent No. 1,109,851, dated Sept. 8th, 1914. The forward end of the socket-piece 22, in advance of the trunnions 21, is formed with a bearing 24 in which is articulated the lower end of the lifting and lowering pawl 25; this latter having, as usual, laterally extending pintles 26 engaging the opposite ends of the bearing 24, one of said ends being open on top, as indicated at 27, for the passage of the stem of the pawl in applying the latter to 15 and removing it from its seat.

Pivoted on a transverse stud 28 (Fig. 4) in the lower portion of the chamber 13 is an upstanding dogging pawl 29 that is formed with an arm 30 on its lower end that extends toward the ratchet wheel 17. This arm 30 is connected with the pawl 25 adjacent to the nose of the latter by an elastic extensible and contractible link designated as an entirety by 31, and best illustrated as 20 to its detail structure in Fig. 3. As therein shown, this link comprises three half-round members or sections 32, 33 and 34, the members 33 and 34 being less than half as long as the member 32 and disposed with their 25 flat sides engaging the upper and lower portions respectively of the flat side of the member 32. To preserve the alinement the engaging faces of the link numbers, which slide endwise on each other, preferably have the tongue-and-groove construction 30 shown in Fig. 3^a; and the members are held in coöperative relation by spiral springs 35 and 36, the former encircling the member 33 and the upper part of member 32, and 35 the latter encircling member 34 and the lower part of member 32. Shoulders 33' and 32' on the members 33 and 32 respectively form end abutments for the spring 35, and similar shoulders 34' and 32^a on the 40 members 34 and 32 form end abutments for the spring 36. The member 33 has at its upper end an apertured extension 37 that engages a pivot stud 38 carried by the lifting pawl 25, and the other short member 34 has at its lower end a similar apertured extension 39 that engages a pivot stud 40 carried by the arm 30 of the dogging pawl 29. The two pawls are thus flexibly connected by the link sections 32, 33 and 34 and their 45 encircling springs 35 and 36.

Manually operable means are provided for placing both of the springs 35 and 36 in compression during the lifting operation so as to cause both pawls to hug the ratchet 50 wheel, these means comprising the following parts. On the lower end of the long link member 32 is an extension 41 (Fig. 3) carrying a lateral pivot stud 42. Pivoted on a stud 43 that is tapped into the end of 55 stud 28 is an elbow lever, one arm 44 of

which has formed in its lower side a notch or half-bearing 45 that engages the upper side of the pivot stud 42. The other arm 46 of the elbow lever is slidingly engaged by a lateral pin or stud 48 carried by a trigger lever 49, said pin 48 in the raised position of the trigger lever (Figs. 1, 7 and 8) engaging a notch 47 in the outer side of lever arm 46 to lock the parts in set position. The trigger lever 49 is fulcrumed on a stud 50 that is tapped into the end of a stud or boss 51 in the lower portion of the chamber 13 parallel to the stud 28 (Fig. 4), and the outer arm of the trigger lever projects through a slot 52 in the rear wall 80 of the chamber 13 of the casing in convenient reach of the operator.

When the jack is to be used for raising a load, the trigger lever 49 is raised to the position shown in Figs. 1, 7 and 8. This, 85 through the elbow lever, draws the long member 32 of the elastic link 31 downwardly, placing both of the springs 35 and 36 in compression, and the latter, acting through the short link members 33 and 34, 90 cause both pawls to hug the ratchet wheel 17. The engagement of the pin 48 with the notch 47 locks the members of the elastic link in their set position while the jack is being operated. Fig. 7 shows the positions 95 of the parts at the limit of a lifting stroke of the handle lever, when the handle lever is in its lowest position and the pawl-controlling link is under its maximum tension. Here the upper spring 35 is compressed by the upward travel of the link member 33 as the pawl 25 travels upwardly, while the lower spring 36 is compressed by the upward movement of the link member 34 caused by the backward swing of the pawl 100 29 acting through its arm 30; both springs at their upper ends abutting against the shoulders 32' and 32^a of the link member 32 which is held stationary by the elbow lever 44. Fig. 8 shows the relative positions of 105 the parts when the handle lever is at the extreme of its upward swing. Here the upper spring is substantially neutral, the lifting pawl being held against the ratchet wheel both by its own gravity and by engagement of the back wall of the pawl seat with the back of the pawl. The lower spring is still under some compression, urging the dogging pawl 29 toward the ratchet wheel, although the load on the lifting bar holds the dogging pawl engaged with the ratchet wheel during the return or 110 upward swing of the handle lever.

When the load is to be lowered, the trigger lever 49 is swung downwardly to the 115 position shown in Figs. 9 and 10. This frees the elbow lever 44 from the locking engagement of the pin 48, and the expansion of the lower spring 36 raises the long link member 32 and, through the pin or 120

70

75

80

90

95

100

105

110

115

120

125

130

stud 42 rocks the elbow lever to the right. Both springs 35 and 36 are then substantially neutral, the load being borne by the dogging pawl. When now the handle lever 5 is swung down, the members 33 and 32 of the link rise slightly, compressing both springs and drawing the pawl 25 beneath a tooth of the ratchet wheel and at the same time compressing the lower spring 36 10 (from its lower end) thereby through the arm 30 urging the dogging pawl away from the ratchet wheel. The dogging pawl is, however, maintained in engagement with the ratchet wheel by the load until, during 15 the final part of the downward swing of the handle lever, there occurs a slight lifting and load-assuming action by the pawl 25 sufficient to free the dogging pawl which then snaps back out of engagement with 20 the ratchet wheel. The relative positions of the parts at this point are illustrated in Fig. 10. As now the handle lever is raised, with the pawl 25 sustaining the load, the link as a whole first contracts and then 25 moves downward bodily, reversing the impulse on the dogging pawl and causing it to engage the next tooth of the ratchet wheel in a position to take the load which it assumes slightly before the handle lever 30 reaches the extreme of its upward swing. During the final part of this upward swing, which releases the pawl 25 from the load, the link is slightly compressed endwise and contracted, as shown in Fig. 9, and the re- 35 action forces the nose of the pawl outwardly clear of the tooth of the ratchet wheel with which it has just been engaged and in a position to engage with the next tooth on the subsequent downward swing of the 40 handle lever.

The foregoing describes the cycle of operations both in raising and in lowering a load. The trigger lever 49 may, of course, be manipulated by hand; but in connection 45 with the handle lever 23 I have provided a simple and convenient expedient whereby the trigger lever may be manipulated in either direction through the agency of the handle lever. Referring to Fig. 5, it will be noted 50 that the outer end of the handle lever is widened and flattened at 23', this widened and flattened portion having a hole 53 formed therethrough that may be slipped over the free outer end of the trigger lever; 55 the handle lever thus serving as a detachable reach handle or like device for manipulating the trigger lever. This is especially convenient when the jack happens to occupy a low position or one otherwise difficult of 60 direct access, as, for instance, beneath an automobile running gear. By giving to the hole 53 the hexagonal form shown the handle lever is also adapted to the purposes of a wrench.

65 Swiveled on the upper end of the lifting

bar 12 by a pivot stud 54 is a head or cap 55 preferably formed with a slightly concave upper face 56. The forward side of the head that overhangs the front side of the lifting-bar 12 is formed with a vertical 70 notch 57 (Fig. 6), and in the opposite side walls of this notch are formed seats or bearings 58. This head or cap 55 is designated to coöperate, in certain situations, with a detachable auxiliary lifting appliance shown in Fig. 1, and comprising a head 59 having a forward depending limb 60 occupying the notch 57 and terminating in a lifting foot 61, and a shorter rear depending limb 62. On the limb 60 are lateral 75 pintles 63 that engage with the seats 58, while the limb 62 is provided on its inner side with a notch 64 that engages with the rear side of the head 55 of the lifting bar in the manner clearly shown in Fig. 1 to 80 form, with the pintles 63, a firm support for the detachable device under a load imposed on its head 59, and also to anchor the device against tilting under a load imposed on the foot 61. This auxiliary detachable 85 appliance not only increases the vertical range of action of the lifting bar in both directions, but, by reason of the swiveled character of the lifting-bar head 55, it enables the jack, through the foot 61, to obtain a hold on objects located behind or on either side of the jack, as well as on objects located in front of the jack. 90

While I have shown my present improvements as embodied in a geared jack, it will 100 be evident that the same may be embodied to equal advantage in jacks of the well known type wherein the pawls coöperate directly with teeth formed on the rear side of the lifting bar. It will also be manifest 105 that the details of construction herein shown and described may be variously modified without introducing any departure from the operative principles involved or sacrificing any of the advantages of the invention. Hence, I reserve all such modifications and changes as fall within the spirit 110 and purview of the appended claims.

I claim:

1. In a jack, the combination of a ratchet member, a lifting pawl, a dogging pawl, an endwise elastic link connecting said pawls, said link comprising end sections articulated to said lifting and dogging pawls respectively, an intermediate section, and independent elastic connections between said end sections and said intermediate section, and means for holding said intermediate section in a position to exert endwise spring pressure through said elastic connections on said 115 end sections.

2. In a jack, the combination of a ratchet member, a lifting pawl, a dogging pawl, an endwise elastic link connecting said pawls, said link comprising end sections articulated 120

125

130

to said lifting and dogging pawls respectively, an intermediate section having sliding engagement with said end sections, and independent compression springs embracing and abutting against said end sections and the end portions of said intermediate section respectively, and means for holding said intermediate section in a position to exert endwise pressure through said springs on said

10 end sections.

3. In a jack, the combination of a ratchet member, a lever-actuated lifting pawl, a pivoted dogging pawl formed with an arm extending toward said ratchet member, an endwise elastic link connecting said pawls, said link comprising end sections articulated to said lifting pawl and to said arm respectively, an intermediate section having sliding engagement with said end sections, and independent compression springs embracing and abutting against said end sections and the end portions of said intermediate section respectively, and means for holding said intermediate section in a position to exert endwise pressure through said springs on said end sections.

4. In a jack, the combination of a ratchet member, a lifting and lowering pawl, a dogging pawl, an endwise elastic link connecting said pawls, said link comprising end sections articulated to said lifting and lowering pawl and said dogging pawl respectively, an intermediate section, and independent elastic connections between said end sections and said intermediate section, and manually operable means for moving said intermediate section endwise to a position wherein it exerts endwise spring pressure through said elastic connection on said end sections and for locking it in said position.

5. In a jack, the combination of a ratchet member, a lifting and lowering pawl, a dogging pawl, an endwise elastic link connecting said pawls, said link comprising end sections articulated to said lifting and lowering pawl and said dogging pawl respectively, an intermediate section having sliding engagement with said end sections, and independent compression springs embracing and abutting against said end sections and the end portions of said intermediate section respectively, and manually operable means for moving said intermediate section endwise to a position wherein it exerts endwise pressure through said springs on said end sections and for locking it in said position.

6. In a jack, the combination of a ratchet member, a lever-actuated lifting and lowering pawl, a pivoted dogging pawl formed with an arm extending toward said ratchet member, an endwise elastic link connecting said pawls, said link comprising end sections articulated to said lifting and lowering pawl and to said arm respectively, an intermediate section having sliding engagement with said

end sections, and independent compression springs embracing and abutting against said end sections and the end portions of said intermediate section respectively, and manually operable means for moving said intermediate section endwise to a position wherein it exerts endwise pressure through said springs on said end sections and for locking it in said position.

7. In a jack, the combination of a ratchet member, a lifting and lowering pawl, a dogging pawl, an endwise elastic link connecting said pawls, said link comprising end sections articulated to said lifting and lowering pawl and said dogging pawl respectively, an intermediate section having sliding engagement with said end sections, and independent compression springs embracing and abutting against said end sections and the end portions of said intermediate section respectively, a pivoted trigger lever, and connections between said trigger lever and said intermediate link section for shifting the latter endwise to a position wherein it exerts endwise pressure through said springs on said end sections and for locking it in said position.

8. In a jack, the combination of a ratchet member, a lifting and lowering pawl, a dogging pawl, an endwise elastic link connecting said pawls, said link comprising end sections articulated to said lifting and lowering pawl and said dogging pawl respectively, an intermediate section having sliding engagement with said end sections, and independent compression springs embracing and abutting against said end sections and the end portions of said intermediate section respectively, a pivoted trigger lever, and a lever between said trigger lever and said link, said last named lever having one arm engaged with the intermediate section of said link, and its other arm adapted to be engaged by said trigger lever to rock the same, whereby to shift said intermediate link section endwise to a position wherein it exerts endwise pressure through said springs on said end sections.

9. In a jack, the combination of a ratchet member, a lifting and lowering pawl, a dogging pawl, an endwise elastic link connecting said pawls, said link comprising end sections articulated to said lifting and lowering pawl and said dogging pawl respectively, an intermediate section having sliding engagement with said end sections, and independent compression springs embracing and abutting against said end sections and the end portions of said intermediate section respectively, a pivoted trigger lever, and a lever between said trigger lever and said link, said last named lever having one arm engaged with the intermediate section of said link, and its other arm adapted to be engaged by said trigger lever to rock the same, whereby

to shift said intermediate link section end-
wise to a position wherein it exerts endwise
pressure through said springs on said sec-
tions, and said levers having coöperating
means for locking them in set position
against the thrust of said springs.

10. In a jack, the combination of a ratchet
member, a lifting pawl, a dogging pawl, link
members, including extensile and contractile
elastic elements, articulated to said lifting
and dogging pawls respectively, a bodily
shiftable coupling member for said link
members through which a thrust or pull on
either may be transmitted to the other, and
15 means for shifting said coupling member to,
and holding it in, a position wherein it con-
stitutes an abutment for the elastic elements
of said link members.

11. In a jack, the combination of a ratchet
member, a lifting pawl, a dogging pawl, link
members, including extensile and contractile
elastic elements, articulated to said lifting
and dogging pawls respectively, an endwise
shiftable intermediate member coupled to
25 said link members through the elastic ele-
ments of the latter and operative to transmit
a thrust or pull on either to the other, and
manually releasable means for shifting said
intermediate member to, and holding it in,
30 a position wherein it constitutes an abut-
ment for the elastic elements of said link
members.

12. In a jack, the combination of a lifting
bar, a head on the upper end of said lifting
35 bar having front and rear portions over-
hanging the latter, and a one-piece auxiliary

lifting appliance detachably mounted on
said head and comprising a head, a down-
wardly and forwardly inclined limb sup-
ported between its ends on the front portion 40
of said lifting-bar head and terminating at
its lower end in a forwardly extending
lifter-foot, and a downwardly and rear-
wardly inclined limb interfittingly engaged
with the rear portion of said lifting-bar 45
head.

13. In a jack, the combination with a lift-
ing-bar having a head formed with a verti-
cal notch in one side thereof and open bear-
ings in the side walls of said notch, of an 50
auxiliary detachable lifting appliance com-
prising a head portion forming a vertical
extension of said lifting bar, a depending
limb lying in said notch and having lateral
trunnions engaging said open bearings and 55
a lifter foot, and an oppositely disposed de-
pending limb notched to engage the side of
said lifting-bar head opposite said notched
side.

14. In a jack, the combination with a lift-
ing bar having a swiveled head formed with
a vertical notch in its front side and open
bearings in the side walls of said notch, of
an auxiliary detachable lifting appliance 60
comprising a head portion forming a verti-
cal extension of said lifting bar, a depending
limb lying in said notch and having lateral
trunnions engaging said open bearings and a
lifter foot, and an oppositely disposed de-
pending limb notched to engage the rear side 65
of said lifting-bar head.

JOSEPH MALICKI.
